CLAIM

The ornamental design for a vehicle deflector, as shown and described.

DESCRIPTION

FIG. 1 is a front and left side perspective view of a vehicle deflector showing my new design;

FIG. 2 is a left side elevation view thereof to which the right side elevation view is a mirror image;

FIG. 3 is a front elevation view thereof; and,

FIG. 4 is a top plan view thereof.

The broken lines shown in the drawings depict portions of the vehicle deflector that form no part of the claimed design.
